2,135,434

HOSE AND SUPPORTER

Eugene F. Gaines, Merion, Pa., assignor to H. Birchard Taylor and Chester W. Larner, both of Philadelphia, Pa.

Application September 16, 1933, Serial No. 689,727

3 Claims. (Cl. 2—240)

My invention relates to elastic hose supporters preferably attached to and comprising a unit with a hose and also to supporters detachable from the hose.

5 A great many attempts have heretofore been made to provide hose supporters that are efficient and comfortable to the user and economical to manufacture, but such prior attempts have had many deficiencies either in their structural or 10 functional aspects, particularly if it were attempted to have the supporter made as an integral part of the hose so as to be washable therewith.

It is one object of my invention to provide an 15 improved supporter in combination with the hose so as to produce a supporter which is hygienic, due to being washable, and which does not restrict the circulation of blood in the leg unduly. It is a further object to provide a supporter having these characteristics by virtue of an improved 20 arrangement of its component elements which lend themselves to the effective use of woven material containing highly elastic threads or fibres which will not deteriorate unduly from washing 25 or from age, exposure to air or perspiration. It is a still further object to have the elements of my improved supporter so arranged that they are preferably devoid of metal attachments, such as 30 hooks, clasps and slides.

35 A still further object is to provide a supporter with a high degree of simplicity of design whereby it may not only be manufactured economically but may be easily and permanently attached to the hose and be made to conform readily to all 40 shapes and sizes of legs without adjustment of slides, clasps or hooks, as such elements are very objectionable in laundering.

45 A further object is to provide a supporter having preferably one or two component elements so as to fit the leg smoothly and naturally without puckering and so as to fold neatly when off the leg.

50 A further and more specific object of the invention is to provide a supporter in which the elements are formed from straight pieces of elastic braid with the ends of one of said straight pieces being connected to the hose to form a loop and the other element, in one specific embodiment of the invention, being suitably connected to the first 55 named element so as to form a loop and to cause the first named element to function effectively in holding the hose in place. As a result of my improved construction, I employ the novel principle of causing the hose to be practically hung on the upper convex curve of the leg muscle instead of

being hung by a vertical strap from a band encircling the leg as in the case of the usual garter designs. Hence in my improved invention the supporter does not grip the leg and is much more comfortable, hygienic and effective.

5 Other objects and advantages will be more apparent to those skilled in the art from the following description of the accompanying drawing in which:

Fig. 1 is a side view of one form of hosiery unit; 10

Fig. 2 is a front view of the same unit;

Fig. 3 is a view of the same unit collapsed and folded flat as it would be when not in position on the leg;

Fig. 4 shows a separate supporter of the same 15 general design as that used in Fig. 3 but provided with catches for attachment to the hose;

Figs. 5 and 6 are side elevations of modified forms of the supporter showing their relation to the hose and user.

20 Referring to Fig. 1, the unit consists of a hose 1 to which is attached by stitching or in other suitable manner a suspension member 2 consisting of a strip of highly elastic webbing or braid in the form of a loop which passes around the back of the leg above the calf muscle, this loop preferably being elastic throughout its length although in accordance with the principles of the invention as herein set forth, the loop may be 25 variously arranged to obtain the necessary extent of elasticity in order to accomplish the results and mode of operation of my invention. A connector member 3, preferably made of similar material, is either permanently or detachably fastened at each end to the suspension member 2 and passes 30 across the front of the leg forming a loop of such length as to draw the suspension member toward the front of the leg and thus hold it more securely to the back of the leg. These two members are 35 preferably connected together by elastic stitching so as not to restrain the stretch of suspension member 2. The latter may be attached to the hose by stitching or in any other suitable manner but this stitching need not be elastic.

40 The effect of the arrangement shown in Fig. 1 45 is practically to hang the hose on the calf muscle of the leg and thus to hold it up securely without gripping the leg unnecessarily. This arrangement of supporter will fit the leg more neatly and without puckering if suspension member 2 is connected to each side of the hose at a point closer to the front of the leg than to the back.

45 The design shown is very simple, consisting merely of two loops of elastic material sewed together and attached to the hose. This design in- 50

volves very little material and labor and is therefore inexpensive. It is more comfortable than the ordinary type of garter, is washable, will fit any size and shape of leg due to the highly elastic properties of the material used and is much more conveniently applied than the ordinary type of garter because it pulls on over the foot with the hose and has no clasps or adjustments.

The form in which the supporter element is made up and attached to the hose is better illustrated in Fig. 3 which shows the hose collapsed and folded flat and the supporter likewise. It will be seen that the suspension member 2 has an end attached to each side of the hose so that it extends vertically upward whereas the connector member 3 is attached to 2 at such an angle that when applied to the leg it will be approximately horizontal.

In the case of a supporter permanently attached to the hose it is important for commercial reasons that it should be possible to fold the supporter neatly and preferably to be able to fold it inside of the hose. This may be done with my invention as indicated by dotted lines in Fig. 3. The suspension member 2 is turned inside out within the hose and the connector member 3 is pushed backward into a reverse position inside the loop of member 2.

A design of separate supporter is shown in Fig. 4. This view shows the supporter folded flat as in Fig. 3 but equipped with clasps 4 for attachment to the hose.

In Fig. 5 the connector and suspension members are arranged to include a loop 8, having its ends adapted for attachment to the hose 1, while a second loop 9 is suitably permanently or detachably connected to loop 8. The loop 8, as shown, passes around the front of the leg and thus serves as a connector and also as a continuation of loop 9 in respect to its function of suspending the hose.

Fig. 6 shows an alternative arrangement, similar to Fig. 1. In this case the suspension loop is made in three pieces, a loop 12 connected at each end to a strip 13. The strips 13 are attached to the hose, permanently or detachably, and to the connector loop 14. Obviously the joints between 12, 13 and 14 may be arranged in various ways without materially affecting the relative positions of the parts or the functioning of the assembly.

In order that the supporter may stretch freely to pass over the foot, may be washed with the hose and may be unaffected by chemicals so that it may be dyed with the hose after attachment thereto, it is preferable that it should be made of braid or webbing containing highly elastic filaments running in a longitudinal direction and that these filaments should be unaffected by ordinary chemicals used in dyeing and present in perspiration and that the elastic material should not deteriorate by exposure to the air as in the case of filaments made from cut rubber which are commonly used in the manufacture of garters. It is also desirable that the component parts of the supporter should be connected by means which do not restrain the stretch of the parts as, for example, by elastic stitching. This insures the parts adjusting themselves to the shape of the leg without puckering and avoids the use of the pivoting or swinging metal hooks customary with the usual type of garter.

The most suitable material for my purpose is described in Patent Numbers 1,822,847 and 1,545,257. My invention, however, is not restricted to the use of this particular material, it being possible to accomplish my results with any material of similar characteristics.

The simplicity of design and mode of use of my supporter may under certain circumstances permit attachment to the hose by any suitable clasps and may also permit either the suspension or connector members, but not both, to be made of non-elastic material although it is of course preferable that both members are elastic to obtain the full functional cooperation thereof.

Obviously it is not essential that the loops of my supporter should be made throughout their length of the same material, although it is usually preferable to do so. The loops are continuous in the sense that they are not made in sections which may be disconnected from each other as in the case of the usual type of garter. They are not continuous in the sense that they must necessarily be made of a single strip of uniform material. Fig. 6, for example, shows a loop composed of the separate portions 12 and 13 permanently connected together.

From a commercial standpoint it is obviously important that a supporter should be attachable to any hose in common use in the trade. In the past, certain types of supporter have been devised which required a special hose provided with tabs or openings in the tops to fit the supporter. This interferes with the universal application of the supporter and such supporters have found little, if any, use. My invention may be attached in various ways to any hose with a uniformly woven top, which is the customary type of manufacture.

It will of course be understood that various changes may be made in the details of construction and arrangements of parts without departing from the spirit of the invention as set forth in the accompanying claims.

I claim:

1. A hosiery unit comprising in combination with a hose, a loop positioned obliquely of the leg and passing around the back of the leg above the calf thereof, a front loop connected to said other loop at an angle thereto when in the unused state and positioned transversely of the leg to pass around the front thereof at a position such as to provide a space between said front loop and the top of the hose, and two strips permanently formed with said loops to form an integral unit therewith, and said strips being connected to the top of the hose on each side of the leg and extending upwardly from the hose substantially longitudinally of the leg and at an angle to said oblique portion.

2. The combination set forth in claim 1 further characterized in that said first-named loop and said strips are made of separate pieces of material stitched together at their ends.

3. The combination set forth in claim 1 further characterized in that said first-named loop and said strips are formed in an angular relation to each other when in the unused state, and means for permanently securing said strips and loop in said angular relation.
